UNITED STATES PATENT OFFICE.

ELISHA N. FALES, OF LAKE FOREST, ILLINOIS.

ANEMOMETER.

Application filed October 19, 1922. Serial No. 595,697.

To all whom it may concern:

Be it known that I, ELISHA N. FALES, a citizen of the United States, residing at Lake Forest, in the county of Lake and State of Illinois, have invented certain new and useful Improvements in Anemometers, of which the following is a specification.

The object of this invention is to provide a simple and easily manufactured rotating member or blade for an anemometer such as an anemometer of the Caselli type.

More particularly my invention contemplates the provision of two aerofoils having flat sides to provide accurate datum lines to aid in the erecting and manufacturing.

Further objects will be more fully explained in the following description and claims. In the drawing:

Fig. 1 represents a front plane view of the anemometer fan.

Fig. 2 represents the two blades or aerofoils of the fan.

Fig. 3 is a side elevation of the fan and mounting showing the mounting in cross section.

Fig. 4 is a section on line 4—4 of Fig. 3.

Fig. 4^a is a modification showing a different cross section of the blade.

Fig. 5 is a modification showing the anemometer blades made integrally out of a single piece of metal or wood.

Figure 6 is an end view of the fan and mounting, the mounting being shown in cross-section.

Numerals 1 and 2 represent the two blades of the anemometer. Blade 1 is provided with a plane surface 3 and blade 2 is provided with a plane surface 4. The opposite sides of the blades 5 and 6 respectively are given an arcuate shape as shown in Fig. 4. Each blade is provided with a semi-circular groove 7 in the plane surface side, and these two grooves exactly fit around the shaft 8 which supports the blades. 9 is a bearing in any suitable support 10 providing a mounting for the anemometer blades. Holes 11 are provided in each blade and bolts 12 extend through these holes 11 and through holes in the shaft 8 to secure the blades to their shaft.

The faces 6 of the blades, instead of being arcuate as shown in Fig. 4, may have any suitable aerofoil section such as shown in Fig. 4^a.

It will be evident that the flat sides of the

blades provide surfaces of reference to aid in erecting and the manufacture of the blades. The grooves may be cut truly at right angles to the edges by modern machinery and these grooves become the means of alignment about the axis. The number of revolutions in such anemometers may be recorded in the conventional manner or may be observed by having the blades painted or colored differently so that the revolutions may be studied either directly by the eye or by the aid of a stroboscope. The low pitch causes a slow speed of rotation which is often highly desirable. Such an anemometer may be used for measuring the air speed of an airplane or may be inserted in a wind tunnel or otherwise fixedly placed for measuring air speed.

In Fig. 5 is shown a modification in which the anemometer vanes are machined out of a single piece of wood or metal or other suitable material. A plane face 3' is first machined in the rough stock and this plane face then furnishes an accurate datum surface so that the stock may be correctly held in place while the other flat surface 4' and the two arcuate surfaces 5' and 6' are machined, and the center hole drilled.

I claim:

1. An anemometer fan comprising two separate blades, each blade having a plane face extending substantially the length and breadth of the blade, and means for joining the blades together.

2. An anemometer device comprising two separate blades, each blade having a plane side provided with a groove, a shaft for supporting the blades, and means for connecting the blades and shaft so that the plane sides of the blades lie in the same plane and the shaft fits within the grooves.

3. An anemometer device comprising a plurality of separate blades each blade having a plane side provided with a semi-circular groove near one end thereof, a shaft adapted to fit within the said grooves, and means extending through the shaft and blades for assembling the blades with the plane sides together and with the axis of the shaft and the plane sides of the blades all on the same geometric plane.

4. An anemometer device comprising a plurality of separate blades, each blade having a plane side provided with a groove near one end, the grooves being adapted to

enclose a supporting member and means for joining the blades and supporting member together.

5. An anemometer fan comprising a plurality of blades, each blade being provided with a flat surface, the length of the said surfaces being nearly as great as the length of the blades.

6. An anemometer fan comprising a plu-

rality of blades, each blade being provided with a flat surface, the length of the said surfaces being nearly as great as the length of the blades, the said flat surfaces being substantially in the same geometric plane.

In testimony whereof I affix my signature.

ELISHA N. FALES.
